UNITED STATES PATENT OFFICE.

LEONARD T. JENNINGS, OF SAGINAW, MICHIGAN.

HOOK FOR GARMENTS.

Application filed September 14, 1925. Serial No. 56,364.

This invention relates to hooks and eyes for garments and the like and the improvement pertains particularly to a novel construction and arrangement of parts of the hook, whereby certain new and useful results are obtained, namely, additional strength is imparted to the hook, the bill of the hook is securely held down to the tape or fabric, and the fabric is prevented from slipping back over the shank of the hook, thereby giving a neat flat closing and preventing the garment gaping.

Another result of my invention is that a hook having the above named advantages can be put on the tape or fabric with one operation and when so placed the pulls to which the hook is subjected in use produce a direct stress upon the hook and fabric instead of a tendency to skew.

My construction also enables the use of a large area riveting or backing plate if desired, so that there can be unusually effective frictional contact between the hook and the fabric and the plate, and greater holding effect.

A still further new result of my improvement is to facilitate hooking together the eye and hook and to prevent tearing.

All of the foregoing results are attained by my invention.

The preferred means by which these results are obtained will now be described and claimed.

In the drawing, Fig. 1 is a plan view of the preferred form of my improved hook.

Fig. 2 is a side view of the hook shown in Fig. 1.

Fig. 3 is a plan view of a modified form.

As is clearly shown in the drawings, my improvement consists in certain modifications of the structure of the ordinary hook now in common use. Such hooks are usually made by bending a wire to provide eyelets 1 and 2 side by side at the base, a bill 3, and the usual tongue 4, which may be made with or without a hump or projection 5, as is well known in the art.

Heretofore the end of the tongue 4 has usually terminated between the two longitudinal members that form the bill 3. Sometimes the end of the tongue terminates between the two bottom members of the bill and sometimes it is bent upwardly and rearwardly and terminates between the two upper members of the bill. In either case, that is, wherever the tongue terminates between

the two members of the bill, serious objection has arisen because of the liability of the tongue to become bent out of the plane of the hook, so the end of the tongue, instead of lying flush between the two side members of the bill, projects and catches fabrics and tears them. Especially is this likely to happen during the cleaning of the garments. The handling to which the garment is subjected in laundries is one of the frequent causes of such displacement of the tongues.

Lack of proper means for holding the bills of the hooks in place upon the tape or fabric has been another disadvantage. Expedients have been employed, but none of them, so far as I am aware, have accomplished the double purpose of preventing the end of the tongue becoming displaced as has just been described, and of holding the bill of the hook in place.

These important results I attain by a simple, yet novel means. I fasten the heretofore free end of the tongue, as well as its base, securely to the fabric at one side of the bill. The bill of the hook is also thereby held down upon the fabric, but it can yield or spring sufficiently to admit the eye.

It will be noted in Figs. 1 and 3, that the eyelet 1 holds down one end of tongue 4 and the eyelet 6 secures its other end.

A further advantage of my preferred construction, shown in Fig. 1, is that the part of the extension of tongue 4 which forms the U-bend is brought underneath the bill of the hook to support it, as at 8 in Fig. 1. The hook is not then likely to be pressed down and made useless, as frequently occurs with ordinary hooks when the garment is being ironed.

In my preferred embodiments of Figs. 1 and 3, the eyelet in the end of the tongue may be utilized as a stop to prevent the fabric being pushed back upon the shanks of the hook, thereby causing the hook to become exposed and permitting the edge of the fabric to become uneven by the repeated fastening and unfastening of the hook and eye.

The new eyelet is indicated by numeral 6. It is preferably formed by extending the end of the tongue 4 and bending the extension back upon itself, so as to enclose in the U-bend thus formed one of the sides of the bill 3 and to support the end of the bill, as at 8. The extremity of the extension is then preferably curled to form the eyelet 6,

disposed in the same plane as the eyelets, 1 and 2 of the ordinary hook.

Thus my hook may have three eyelets, instead of the usual two, and when all of these eyelets are riveted to a single backing plate 9, great additional strength to resist pulling strains is imparted to the hook. It is not possible for the bill of the hook to lift away from the tape or fabric and the third eyelet may be utilized to prevent the fabric from slipping back on the hook.

By the means above described I have produced a simple and inexpensive garment hook that accomplishes all of the results set forth in the statement of the objects of my invention.

Having thus described my invention, what I claim and desire to secure by Letters Patent is:

20 1. A fabric-securing hook of the class described having eyelets at its base and a tongue having its main portion centrally disposed and its end portion bent laterally

to extend under and constitute a support for the bill of said hook, the end of said tongue 25 formed with an eyelet, said eyelet positioned at one side of said bill.

2. A fabric-securing hook of the class described having eyelets at its base and a central tongue extending lengthwise the hook 30 for a part of the length of said hook, the end portion of said tongue bent laterally to extend underneath the bill of said hook near its end, the end portion of said tongue formed with an eyelet located at one side 35 of said bill.

3. A fabric-securing hook of the class described having eyelets at its base and a tongue having its main portion centrally disposed, and its end portion bent laterally 40 to extend under and constitute a support for the bill of said hook, the extremity of said tongue projecting laterally beyond the side of said bill, for the purposes set forth.

In testimony whereof, I affix my signature.

LEONARD T. JENNINGS.
